GELATIN DYNAMITES

Clarence Herman Winning, Woodbury, N. J., assignor to E. I. du Pont de Nemours & Company, Wilmington, Del., a corporation of Delaware

No Drawing. Application September 26, 1942,
Serial No. 459,841

8 Claims. (Cl. 52—7)

This invention relates to gelatin dynamites.

By the term gelatin dynamites, I intend to include all explosive compositions containing a liquid explosive ingredient and nitrocellulose. That is, my invention is applicable to straight gelatins, ammonia gelatins, semi-gelatins, blasting gelatins, and the like.

The problem in the manufacture of gelatin dynamites, for certain purposes, is to produce a very stiff and viscous material; however, it is not always convenient to manufacture such a product. Previously, if a stiff gelatin were desired excess nitrocellulose was added. A disadvantage in the manufacture of exceptionally stiff gelatin dynamites, in accordance with the prior art, is the high cost of production due to the excess nitrocellulose necessary to produce such a product.

The plasticity of gelatins must be controlled within reasonable limits during manufacture in order to obtain normal cartridge operations on automatic machinery used for this purpose. Therefore, difficulties occur when an exceptionally stiff explosive is desired as would be the case for gelatins which have to be forced through heavy muck to considerable depths in order to charge the bore hole. Certain gelatins when exposed to the sun or exceptionally high temperature become undesirably soft for certain types of loading operations.

An object of the present invention is the production of gelatin dynamites having substantially higher viscosities and stiffness than have heretofore been practicable. A further object is the production of gelatin dynamites which maintain high viscosities and satisfactory plasticity over long periods of heated humid storage. An additional object is the manufacture of gelatins having enhanced properties over those previously produced for use, particularly in seismograph prospecting. Other objects will appear as the invention is further described.

I have found that the viscosity and stiffness of the gels can be greatly increased, within a substantially short time after processing, by the addition of certain metallic compounds, herein referred to as gelation agents. If one of these inorganic gelation agents is added to nitroglycerin-nitrocellulose gel, the viscosity or character of the gel may be changed to the extent that it becomes set or semi-rigid. The most effective gelation agents, according to my invention, include compounds of lead, for example lead hydroxide ($Pb(OH)_2$); a basic lead nitrate, one simple form of which may be indicated by the formula ($Pb(OH)NO_3$); litharge (PbO); red

lead (Pb_3O_4); and other compounds of lead. However, I find that other metallic compounds are applicable, for example ferric sulfate ($Fe_2(SO_4)_3$); a basic ferric sulfate, one simple form of which may be indicated as $FeOH_2SO_4$; and similar compounds of copper, manganese, aluminum, bismuth, mercury, and cobalt. The amount of said gelation agents used preferably will be between 0.05 and 5%, based on the weight of the liquid explosive nitric ester.

It is believed that in some instances these metallic compounds are changed somewhat in a gelatin during storage by reactions involving sodium or ammonium nitrate, antacids, and moisture. For example, it is possible that some lead oxide is converted to basic nitrate or that some aluminum sulfate is converted to a basic aluminum sulfate. These reactions do not necessarily go to completion. It is possible, therefore, that the reaction products, rather than the materials introduced, are responsible for the improved effect.

The foregoing gelation agents according to this invention are advantageous when used in conjunction with gelatinized high explosives generally, inasmuch as they increase the viscosity and stiffness of the same. This invention is applicable with high efficiency in case of the straight and ammonia gelatins as well as with the so-called semi-gelatins where smaller percentages of nitrocellulose are present. In addition, I have discovered that said gelation agents are effective in nitroglycerin containing nitrated polymerized glycerin and ethylene glycol, or mixtures of these with nitrated glycerin.

Further illustration of my invention is furnished in the following examples of blasting gelatins prepared with said gelation agents.

Table I

		A	B
40	Nitroglycerin.....	per cent.	91.0 90.8
	Nitrocotton.....	do	4.5 4.5
45	Lead hydroxide.....	do	0.2
	Combustibles.....	do	3.5 3.5
	Chalk.....	do	1.0 1.0
	Hardness (penetration tester):		
	1 day.....	1	2
	2 months 35° C.....	0	4
50	Density: As produced.....	1.34	1.34

The hardness experiments were carried out by means of a pin $\frac{3}{8}$ " in diameter at the penetration end. A force was applied to the pin by means of a spring. The hardness figures show that increased tension from the spring was necessary to obtain the same depth of penetra-

tion of the pin. The unit of these figures is arbitrary.

The increased hardness of the finished explosive, a modified blasting gelatin, in column B of the above table shows the desirable effect of lead hydroxide as one of my gelation agents. It will be apparent that this gelatin increased in stiffness during two months' storage at 35° C.

The increased hardness brought about by operation according to this invention may be strikingly illustrated by the following results in which lead oxide was used as a gelation agent in a 60% straight gelatin.

Table II

	A	B
Nitroglycerin.....	percent	50.0
Nitrocotton.....	do	2.2
Sodium nitrate.....	do	31.6
Combustibles.....	do	13.8
Lead oxide.....	do	1.0
Chalk.....	do	2.4
Hardness (penetration tester):		
1 day.....	4	11
2 months 35° C.....	4	11
Density: As produced.....	1.43	1.44

To further demonstrate the gelation effect of my metallic compounds on gelatinized high explosives, extrusion tests were carried out on these explosives, and as an example, I cite the test made on the modified blasting gelatin in Table I above, in which lead hydroxide was used as the gelation agent. In this experiment 300 grams of the gelatin were placed in a container with $\frac{1}{4}$ " hole in the bottom. A similar apparatus was set up to test the stiffness of the same gelatin in which gelation agents were absent. These explosives were tested under 50° C. and the same pressure. After three days' storage under these conditions, 63.5 grams of the explosive in which gelation agents were absent had exuded through the hole; whereas, all of the explosive which contained an amount of lead hydroxide between 0.2 and 1% remained in the container.

The beaker viscosity or pour test data on stored gels shown below give evidence that the metal salts, according to this invention, exert a gelation effect against the viscosity-reducing effect of certain materials in gelatinized high explosive compositions. These explosives were stored at 35° C. and 75% relative humidity. They were prepared by stirring ten minutes at 50° C. The degree of gelatinization is indicated by the time required for the material to flow a given distance at a definite angle of inclination. I indicates that the flow was practically instantaneous. The fractions in these tables indicate that the material flowed only the indicated fraction of the fixed distance in five minutes. Longer timing periods were not considered convenient or particularly significant.

The table below shows the gelation effect of metal salts in the presence of ammonium nitrate, which is present in ammonia gelatins.

Table III

	1 day	1 mo.	4 mos.	9 mos.
	Inches	Inches	Inches	Inches
Standard—no metal salt	50	3	1	1
1.0% ferric sulfate	62	70	65	34
1.0% ferrous sulfate	90	120	24	30
1.0% aluminum sulfate	45	50	10	7

The following table indicates the gelation ef-

fect in gelatins containing sodium nitrate, which is present in straight gelatins.

Table IV

	1 day	1 wk.	1 mo.	2 mos.
	Inches	Inches	Inches	Inches
Standard—no gelation agent.....	43	45	40	40
0.2% litharge.....	60	1 $\frac{1}{2}$	1 $\frac{1}{2}$	(1)
0.2% lead hydroxide.....	300	1 $\frac{1}{2}$	1 $\frac{1}{2}$	(1)
0.2% basic lead nitrate.....	2 $\frac{1}{2}$	1 $\frac{1}{2}$	1 $\frac{1}{2}$	1 $\frac{1}{2}$

¹ Practically set.

The following table serves as an illustration of the stabilizing effect the gelation agents have on the viscosity of gelatin explosives, made in accordance with my invention, in the absence of other inorganic nitrates.

Table V

	1 day	1 wk.	1 mo.	2 mos.
	Inches	Inches	Inches	Inches
Standard—no gelation agent.....	51	60	52	50
0.2% litharge.....	60	97	56	56
0.2% lead hydroxide.....	198	2 $\frac{1}{2}$	2 $\frac{1}{2}$	2 $\frac{1}{2}$
0.2% basic lead nitrate.....	269	2 $\frac{1}{2}$	2 $\frac{1}{2}$	2 $\frac{1}{2}$

In carrying out my invention, nitroglycerin may be used alone as the liquid explosive nitric ester if desired, although other liquid nitric esters, for example ethylene glycol dinitrate, may be employed either alone or in combination with nitroglycerine. Moreover, other nitric esters and nitro compounds may be present also dissolved in the liquid nitric ester. Furthermore, such materials may be used for making the explosive composition more resistant to freezing.

Explosive compositions produced according to this invention possess material advantages over similar compositions of the prior art. For example, the finished explosive retains its initial high degree of stiffness and causes no increased difficulties in working properties. Similar retention of the desired properties, characterizing the explosive compositions as originally processed, is made possible without the use of excessive amounts of nitrocellulose.

It is to be understood that the invention is not to be limited to the specific examples and details herein described, since these can be varied without departing from the scope of this invention. Therefore, I intend to be limited in my invention only as indicated in the appended patent claims.

55 I claim:

1. A gelatin dynamite comprising a liquid explosive nitric ester, nitrocellulose, and a compound taken from the group consisting of metallic oxides, hydroxides, normal and basic salts of elements taken from the group consisting of lead, iron, and aluminum, said compound being present in an amount between 0.05 and 5%, based on the weight of the liquid explosive nitric ester.
2. The gelatin dynamite of claim 1, in which the gelation agent is lead hydroxide.
3. The gelatin dynamite of claim 1, in which the gelation agent is a basic lead nitrate.
4. The gelatin dynamite of claim 1, in which the gelation agent is lead oxide.
5. The process of controlling the gelatinization of nitrocellulose in a liquid explosive nitric ester, which process comprises effecting said gelatinization in the presence of a compound taken from the group consisting of metallic oxides, hy-

75

dioxides, normal and basic salts of elements taken from the group consisting of lead, iron, and aluminum, said compound being present in an amount between 0.05 and 5%, based on the weight of the liquid explosive nitric ester.

6. The process according to claim 5, in which said gelatinization is brought about in the presence of lead hydroxide.

7. The process according to claim 5, in which said gelatinization is brought about in the presence of a basic lead nitrate:

5 8. The process according to claim 5, in which said gelatinization is effected in the presence of a lead oxide.

CLARENCE HERMAN WINNING.
